Primary Examiner — Clare E Heflin(74) *Attorney, Agent, or Firm* — Brouillette Legal Inc.;
Damien Calvet(57) **CLAIM**

The ornamental design for a light, as shown and described.

DESCRIPTION

FIG. 1 is a bottom perspective view of a light;

FIG. 2 is a top perspective view of the light;

FIG. 3 is a top plan view of the light;

FIG. 4 is a side elevation view of the light; and,

FIG. 5 is a bottom plan view of the light.

The broken lines shown on the drawings depict portions of the light that form no part of the claimed design.
